[57] CLAIM

The ornamental design for a savings bank, as shown and described.

DESCRIPTION

FIG. 1 is a top plan view of a savings bank showing our new design;

FIG. 2 is a front elevational view of the savings bank showing our new design;

FIG. 3 is an elevational; view of one side side of the savings bank showing our new design, (other side corresponds);

FIG. 4 is an underplan view of the savings bank showing our new design;

FIG. 5 is a rear elevational view of the savings bank showing our new design;

FIG. 6 is a perspective view from the front, above and one side of the savings bank with a coin receiving slide in a fully raised, coin receiving position, showing our new design, (other side corresponds);

FIG. 7 is a front elevational view of the savings bank with the coin receiving slide in a partly lowered, coin depositing position showing our new design;

FIG. 8 is a top plan view of a savings bank with the coin receiving slide fully raised and with a coin receiving tray thereof in a coin receiving position, showing our new design; and,

FIG. 9 is a rear elevational view of the savings bank with a lower portion of the base broken away and the coin receiving slide in a fully raised position and with a coin receiving tray thereof in a coin receiving position, showing our new design.
